UNITED STATES PATENT OFFICE.

ERNEST WALTON AND FREDERICK W. MACKE, OF KOKOMO, INDIANA, ASSIGNEES TO H. B. SHERMAN MANUFACTURING COMPANY, OF BATTLE CREEK, MICHIGAN, A CORPORATION OF MICHIGAN.

NAIL-MAKING MACHINE.

No. 919,095.

Specification of Letters Patent.

Patented April 20, 1909.

Application filed December 7, 1907. Serial No. 405,597.

To all whom it may concern:

Be it known that we, ERNEST WALTON and FREDERICK W. MACKE, of Kokomo, Howard county, Indiana, have invented certain new and useful Improvements in Nail-Making Machines; and we hereby declare that the following is a full, clear, and exact description thereof, reference being had to the accompanying drawings, which form part of this specification.

This invention is an improvement in nail making machines, and is a novel machine especially designed for making roofing nails having large sheet metal heads and wire shanks.

The object of the invention is to provide a machine whereby the wire from which the shanks are formed, and the strap-metal from which the heads are formed, are fed forward on intersecting lines, and, preferably, in its operation a proper length of wire is fed toward the operating point and clamped by suitable dies; and a proper length of strap-metal is fed toward the operating point and stopped; then a disk or nail head is punched from the strap and simultaneously forced onto the end of the wire, the wire punching the head; then the head is preferably concavo-convexed by a further movement of the punching dies; then the shank is riveted to the head by means of a header-rod which preferably operates through the male punching die. Then the heading and punching dies are retracted and the wire, with the attached head, is again fed forward the length of a nail; then the complete nail is severed from the wire by means of cutting dies, which preferably are also pointing dies. The feeding forward of the wire with the attached head, is merely a repetition of the first mentioned step of feeding the wire; and when the nail is severed from the wire, the end of such wire is in position to have another head attached thereto. The wire is clamped after each nail is severed therefrom and remains clamped until another head has been attached thereto as described. Thus at each operation of the machine a nail-head may be blanked from the strap metal, forced onto the end of the wire, and concavo-convexed, and the wire is swaged thereto; then the wire is fed forward a nail length, and a complete nail is severed therefrom. This cycle of operations is completed for each operation

of the machine, and preferably for each rotation of the main shaft thereof.

The invention will be more clearly understood from the following description of the machine illustrated in the accompanying drawings which represent a practical embodiment of the invention and the essential features thereof, and the construction and combination of parts constituting the invention and for which protection is desired herein, are set forth in the appended claims.

In said drawings—Figure 1 is a top plan view of the machine. Fig. 2 is a side elevation of Fig. 1. Fig. 3 is an enlarged plan view of the die-portions of the machine, with the strap feeding devices removed—and the dies opened. Fig. 4 is a horizontal section through Fig. 4, with the dies closed. Fig. 5 is a transverse vertical section on line 5—5, Fig. 3. Fig. 6 is a transverse section on line 6—6, Fig. 1. Fig. 7 is a view similar to Fig. 4 showing the position of the parts previous to the nail being headed. Fig. 8 is a detail vertical sectional view on line 8—8, Fig. 5. Fig. 9 is a detail sectional view on line 9—9, Fig. 8. Fig. 10 is a detail view of the wire clamping dies. Fig. 11 is a perspective view of a complete roofing nail. Fig. 12 is a side elevation of the drive side of the machine. Fig. 13 is a bottom plan view partly broken away; and Fig. 14 is a plan view of the strap feeding device.

The wire *w* is led from a reel or coil (not shown) and fed by suitable means to the clamping die, which is preferably composed of similar opposite parts 1, 1, (see Figs. 3, 4, 90 and 10); each part 1 has a wire guiding channel 1^a adapted to firmly bite the wire *w* when the die is closed thereon. The opposite parts 1 of the clamping die are respectively secured to a fixed die block 2 and a slidable die block 2^a, which latter can be moved to and from the former to open and close the clamping die by any suitable means. The parts 1, 1, are removably secured in recesses in the opposed adjacent faces of blocks 2, 2^a, 95 by means of set screws 2^b, as shown.

As shown, the movable die block 2^a is operated by means of a push-pin 2^b interposed between the block 2^a and short arm of a lever 2^c, pivoted to a pin 2^d attached to the top of the main frame; and the long arm of lever 2^c carries a roller 2^e which engages a cam 2^f attached to the main shaft *S*, which

is suitably journaled in bearings F' on the top of the main frame. The roller 2^d may be held in contact with the cam 2^e by means of a spring 2^h as shown in Fig. 1, such spring tending to move the lever and cause block 2^a to separate from block 2 and open die 1. The block 2^a may be connected to the lever 2^c by a link 2^x of any suitable kind, so that it will be drawn away from block 2, and open die 1, when the lever 2^c is moved by spring 2^h . A bolt 2^y may be tapped through the lever 2^c and engage pin 2^b , so as to regulate and adjust the amount and time of pressure exerted by cam 2^e upon the dies through lever 2^c . The block 2 may be adjustably mounted in a holder casting 2^k securely attached to a projection F^2 on top of the main frame; said block 2 being secured in position by bolts $2^l, 2^m$. The block 2^a preferably has a dove-tailed groove-and-slot connection with the holder 2^k as shown.

The parts 1, of the wire clamping die, also form, in the example shown, the female member of the blanking die for cutting the nail-heads out of the metal strap s . As shown in Figs. 3, 4, 7, 10, the forward end of parts 1, 1, are provided with opposite semi-circular recesses $1^b, 1^b$, which when the die is closed form a circular chamber or die, concentric to the wire groove 1^e , (see Figs. 4, 7 and 10) and preferably the bottoms of the recesses $1^b, 1^b$, are convexed as shown at 1^e , for a purpose hereinafter described.

3 designates a male blanking die which is adapted to coöperate with the female blanking die 1^b in the ends of clamping die 1 and cut a circular nail head from the metal strap s which is fed between the dies 1 and 3 and across the line of the wire feed by suitable means as hereinafter explained. This male blanking die 3 is removably fastened to a slide 3^a which is guided in a box F^3 attached to the top of the main frame, and said slide has an extension 3^b which is attached to an eccentric box 3^c inclosing an eccentric or crank 3^s on shaft S , so that for each rotation of shaft S the die 3 is moved to and from the die 1.

Arranged within the die 3 is a header-rod 4, which is adapted to operate through an axial bore in the die 3 and slide 3^a and is connected to a slide 4^a , guided in a box F^4 on the frame, and connected to an eccentric-box 4^c inclosing a crank 4^s on shaft S .

55 Located in front of the blocks 2, 2^a , are cutting and pointing dies 5, which are preferably detachably secured in recesses in blocks 5^a adjustably secured to arms 5^b pivotally mounted on rods f attached to brackets f' depending from the main frame. These arms 5^b may have depending portions 5^c against which press springs 5^b which are so arranged as to tend to rock the arms 5^b and normally separate the cutting dies 5.

65 As shown in Figs. 5, 8 and 9, the cutting

die 5 is secured in block 5^a , by tap-bolts 5^e . The block 5^a is adjustable vertically on arms 5^b , by means of a setting bolt 5^f , and can be fastened where adjusted by means of a threaded shank 5^g and nut 5^h , these various adjustments providing means for adjusting the cutting and pointing dies 5 accurately.

The cutting dies are moved inward toward the wire at the proper time by means of levers 5^k which may be pivoted at 5^l on top of the main frame, and have bolts 5^i tapped through their short arms engaging the blocks 5^a as shown in Figs. 1 and 3. The long arms of said levers 5^k carry rollers 5^j engaging grooved cams 5^s fastened on shaft S as shown.

The wire w may be fed forward to dies 1 by any suitable means. As shown, it is first passed through a straightener W , of any suitable construction, attached to one end of the main frame, and then led between a fixed jaw 6^a and a pivoted jaw 6^b attached to a slide 6, the jaw 6^b being actuated by a spring 6^c and adapted to bite the wire when the slide 6 moves inward toward the dies and to slip on the wire when the die moves away from the dies. The slide 6 is supported by a rod 6^e guided in bracket F^6 attached to the main frame and to one end of slide 6 is pivoted a rod 6^f connected to one end of an oscillating lever 6^g which is pivoted on a bolt 6^h on the main frame, and the other end of lever 6^g is connected by a rod 6^i to a pin 6^j adjustably secured to a block 6^s fastened on shaft S . The connection between rod 6^f and lever 6^g is preferably an adjustable one, as indicated at 6^m , so that the throw of the slide 6 can be varied according to the length of wire it is desired to feed into the machine at each operation. The length of wire fed determining the length of the nail shanks.

The strap s may be fed vertically downward between the dies 1 and 3 by means of rollers 7 on shafts 7^a journaled in a bracket F^6 mounted on top of bracket F^2 , the said shafts 7^a have intermeshing gears 7^b , and on one of said shafts is a ratchet 7^c which is engaged by a pawl 7^d pivoted to lever 7^e loosely mounted on such shaft 7^a and oscillated thereon by means of a link 7^f attached to an eccentric strap 7^g and surrounding an eccentric 7^s on shaft S . The strap s is led in from a reel (not shown) through a suitable guide to the rolls 7. As shown it is passed through a guide slot 7^k in a bar 7^m attached to casting F^6 above the rolls, said slot having a spring actuated presser plate 7^l at one end, which tends to keep the strap properly aligned against the opposite end of the slot.

Preferably the wire is roughened or barbed so as to cause the nail to take a better hold in the wood. This may be accomplished in any way desired, as by milled feed rolls. As shown in Fig. 4, the wire grooves 1^e in the parts 1 of the wire clamping die may be

ridged as at 1^u ; so that when closed upon the wire they will roughen the same as indicated. The shaft S may be driven in any suitable manner, and with each revolution thereof the machine goes through a cycle of operations and produces a complete nail. The cams and eccentrics are so adjusted on shaft S that the parts all operate in proper time and sequence, and the operation is briefly as follows: Assuming that the wire w has been properly fed forward through the clamping die 1, its end projecting into the recess 1^a as indicated in Figs. 3-7, and that meanwhile the strap s has been fed down until its end lies between the dies 3 and 1, die 3 being in retracted position, the die 1 is then closed upon the wire by the coöperation of cam 2^s and lever 2° , and while the wire is thus clamped the slide 6 moves backward preparatory to again feeding the wire. While the wire is thus clamped by die 1, the blanking die 3 moves forward and catches the metal strap s , (which has been previously fed down between the dies 3 and 1, see Fig. 3), and punches a preferably circular disk or nail-head H from this strap and forces said head into the female blanking die 1^b and against the projecting end of the wire, causing the latter to perforate the head; and after the blank is forced upon the wire (see Fig. 7) the head is preferably concavo-convexed by compression between the convex bottom 1^c of die 1^b and the concave face of die 3 (see Figs. 4 and 7). Then while the head H is tightly held between the dies 1 and 3 and the wire tightly held by the clamping die, the header-rod 4, which has been following up the die 3, comes into contact with the end of the wire projecting through the head and swages the same to the head as shown at h in Fig. 4. The parts of the clamping die are preferably slightly recessed around the inner ends of grooves 1^a , as shown at 1^t in Figs. 4-7, so that a portion of the metal of the wire will be forced back and swaged against the inner side of the head, as shown at h' in Fig. 4, and thus the head is united to the wire shank in a perfectly rigid and secure manner. The header-rod 4 then retreats, being followed up by die 3, and the block 2^s is moved so as to open the clamping die and release the wire; whereupon the wire is fed forward so as to push the completed head and attached part of the wire, out of the blanking die or recess 1^b a distance equal to the desired length of the shank of the nail. Then, while the die 3 and header-rod 4 are retracted (see Fig. 3), the cutting and pointing dies 5 are caused to move inward and sever a nail length, with the head attached, from the wire. The severed and completed nail drops out of the way before the die 3 again brings the strap s against die 1. The strap feed is operated in proper time to feed in a sufficient

length of strap to enable a new head to be punched therefrom at the next operation of die 3. The block 2^s is then again moved to cause the clamping die to clamp the wire; and the cycle of operations is repeated. Thus far and during each rotation of shaft S a complete nail as shown in Fig. 11, is formed in the manner described.

It is obvious that various changes may be made in the forms and dimensions of parts and their connections and in various features or elements of the machine, particularly in the wire feed, strap feed, the form or construction of the dies and the means of operating the dies, while the essential features of the invention by which the headed roofing nails are produced are retained. We therefore do not restrict ourselves to the precise structure shown in the drawings.

Having described our invention what we claim as new and desire to secure by Letters Patent is:

1. In a wire nail machine, the combination of a wire clamping die, a female blanking die at one end of the wire clamping die, a male blanking die coöperating with the female blanking die, a header rod arranged axially within the male clamping die, and means for operating said dies and header rod.

2. The combination of a wire clamping die formed of opposite members having wire clamping grooves in their opposed faces, and recesses in their outer ends forming a female blanking die; with a male blanking die adapted to coöperate with the female blanking die when the clamping die is closed, substantially as described.

3. The combination of a wire clamping die formed of opposite members having wire grooves in their opposed faces and recesses in their outer ends forming a female blanking die concentric to the wire; with a male blanking die adapted to coöperate with the female blanking die when the clamping die is closed; a header rod operating axially of the male blanking die; and means for operating said dies and header rod.

4. The combination of wire clamping dies, head blanking dies in axial alinement therewith, a header rod operating through the blanking dies and means for operating the wire clamping and head blanking dies and header rod.

5. In a nail making machine the combination of wire clamping dies, means for feeding a wire to said dies, means for feeding a strap in front of the clamping dies, means for blanking a nail head from the strap and forcing it upon the wire shank held by the clamping dies, means for swaging the shank to the head, and means for thereafter cutting the wire into nail lengths.

6. In a nail making machine the combination of means for feeding a wire; dies for holding the wire; means for feeding a strap

to intersect the wire; means for blanking a nail head from the strap; means for swaging the wire to the head; and means for subsequently severing the wire into nail lengths.

5 7. In a nail making machine the combination of means for feeding a wire; dies for holding the wire; means for feeding a strap to intersect the wire; means for blanking a nail head from the strap and forcing it upon the 10 wire, the wire puncturing the head; means for swaging the wire to the head; and means for severing a nail length having the head attached,—from the wire.

8. In a machine for making roofing nails, 15 the combination of a wire clamping die; means for feeding a strap across the line of the wire feed; dies for blanking a head from the strap and forcing it upon the end of the wire held by the dies, the wire puncturing the 20 head; means for then swaging the end of the wire to the head; means for feeding the wire forward through the clamping die after the head is attached thereto; and means for severing a nail length of wire—having the head 25 attached—from the wire.

9. In a nail making machine, the combination of wire feeding means; a wire clamping die; means for feeding a metal strap across the line of wire feed, a female blanking die at 30 the end of the wire clamping die, a male blanking die opposite the female die; means for swaging the head to the wire, and means for severing a nail length from the wire after the head is attached thereto.

35 10. In combination, a wire clamping die; means for opening and closing said die; means for feeding a wire through said die when opened and after the head has been attached thereto; head blanking dies in axial 40 alignment with the clamping die; means for feeding a metal strap across the line of wire feed and between the male blanking die and the clamping die, and means for operating the blanking die to cut a head from the strap

and force it upon the end of the wire held by 45 the clamping die; with means to rivet the wire to the head, and means for severing a nail length from the wire after the head has been attached thereto.

11. In a nail making machine, the combination of means for feeding a length of wire; a die for clamping the wire; means for feeding a metal strap; dies for blanking a head from such strap and impaling it upon the end of the wire held in the clamping die; means 55 for swaging the wire to the head, the wire feeding means operating to move the wire forward after the head is attached; and means for thereafter severing the headed portion of the wire into a nail length, and 60 pointing the nail.

12. The combination of a wire clamping die, wire cutting and pointing dies on opposite sides of the line of wire feed, means for operating said pointing dies and means for 65 feeding a wire through the clamping dies; with means for feeding a metal strap across the line of wire feed, and means for blanking heads from said strap and impaling same upon the end of the wire prior to the sever- 70 ance thereof.

13. In a nail making machine the combination of wire clamping dies, means for opening and closing the same, a female blanking die at one end of the clamping dies, a male 75 blanking die, means for reciprocating said male blanking die, a header rod arranged axially of and operating through the male blanking die, and means for operating said header rod.

In testimony that we claim the foregoing as our own, we affix our signatures in presence of two witnesses.

ERNEST WALTON.
